DESIGN FOR A PRESCRIPTION BOTTLE

Ralph J. Gelinas, South Weymouth, and Charles J. Conley, Wellesley Hills, Mass., assignors to United Drug Company, Boston, Mass., a corporation of Delaware

Application March 31, 1941, Serial No. 100,044

Term of patent 14 years

To all whom it may concern:

Be it known that we, Ralph J. Gelinas and Charles J. Conley, citizens of the United States and residents of South Weymouth, Massachusetts, and Wellesley Hills, Massachusetts, respectively, have invented a new, original, and ornamental Design for a Prescription Bottle, of which the following is a specification, reference being had to the accompanying drawing, forming part thereof, in which

Fig. 1 is a front elevational view of a prescription bottle, showing by new design;

Fig. 2 is a rear elevational view thereof;
Fig. 3 is a left side elevational view thereof;
Fig. 4 is a bottom plan view of the same; and,
Fig. 5 is a sectional view taken along the line 5—5 in Fig. 1.

The characteristic features are shown in full lines.

We claim:

The ornamental design for a prescription bottle, substantially as shown and described.

RALPH J. GELINAS.
CHARLES J. CONLEY.
